COLLAR AND CUFF STARCHING
MACHINERY

George L. Campf, Portland, Oreg.

Application June 24, 1944, Serial No. 541,982

4 Claims. (Cl. 91—51)

My invention relates to collar and cuff starching machines having a bottom feed roll in combination with a plurality of top press rolls in arcuate arrangement with said bottom feed roll and adapted to starch collars and/or cuffs without starching the shirt body and to carry out the starching operation in a more efficient manner.

The object of my invention is to save time and material and to improve the quality of the work turned out.

My objectives are obtained thru the use of the machine illustrated in the accompanying drawings and minutely described in the specification.

Throughout the drawings and the specification similar numerals refer to similar parts.

Fig. 1 of the drawings is a plan view with the upper press rolls removed; Fig. 2 is a vertical section on the line 2—2 of Fig. 1; Fig. 3 is a vertical section on the line 3—3 of Fig. 1; Fig. 4 is an enlarged section on the line 4—4 of Fig. 3.

Prior to the war when labor was not such an item, collars and cuffs were dipped in the starch and wrung out by hand. Since labor became scarce and costly the starch is put in an ordinary washing machine and the entire shirt agitated therein. The average customer does not want an all starched shirt. The laundry operator must look to the cost of labor and material and to the satisfaction of the customer if he is to stay in business.

Quality in starch work means the elimination of high or bright spots or streaks. These are caused by an excess of starch which burnishes during ironing and causes high-lighted spots or streaks on the collars or cuffs.

Several attempts have been made to provide a machine which would distribute the starch throughout a collar or cuff in a satisfactory manner without getting it into the body of the shirt. In each instance a combination of two rolls one above the other was used. These arrangements have not proved satisfactory.

I discovered that by using a plurality of press rolls I could distribute the starch more evenly throughout the collar or cuff and leave the same in better condition for ironing. The arrangement of these rolls will now be described in conjunction with the complete machine.

The base 1 of the machine is made hollow for the reception of the starch pan 2 to which is attached the heating element 3 provided with an aquastat 4 which extends into the liquid starch 5 in the pan 2 so that the aquastat may control

the operation of the switch (not shown) thru which electricity flows to the heating element 3 thus permitting the starch to be kept at the desired temperature. If cold starch is used the 5 heating element, aquastat, and switch, may be dispensed with.

In the top of the base 1 is mounted a roll 6 to which is secured a relatively firm rubber cover 7. This roll 6 is journaled in the bearings 8 in the base 1 and extends into the starch 5 so that the same may be raised out of the pan during the revolution of the roll. The roll 6 is revolved thru the agency of the motor 9 and the reduction gear 10 which is connected to the roll shaft 11 by the flexible coupling 12. The reduction gear is mounted on the bracket 13 formed on the side of the base 1. I find that a roll 12" in diameter operated at about 10 R. P. M. to be very satisfactory. It is to be seen that the speed reduction 15 may be had thru a system of pulleys and that another prime mover may be used in lieu of the motor.

The base 1 is provided with the hinge lugs 14 for the reception of the hinge pins 15 which engage the lugs 16 formed on the top 17 whose top surface 18 forms the support for the work being passed between the lower roll 6 and the upper press rolls 19, 20, 21, 22, and 23. The use of five rolls has been found to be very satisfactory. 20 However, no limitation as to this number is to be construed. Each of the above press rolls is rotatably mounted in its respective bearing carriers 19A, 20A, 21A, 22A, and 23A, which are 25 slidable in their respective guideways 19B, 20B, 21B, 22B, and 23B. These guideways are shown 30 formed as part of the arms 24 which are cantilevered out from the base 25 secured to the top 17 by the cap screws 26. When the press rolls 19 to 23, inclusive, are cantilevered out over the 35 bottom roll 6, the arrangement may be termed open-ended. The open end is designated by the letter A. This open-ended arrangement permits the collars and cuffs only of a shirt to be passed 40 between the upper and lower rolls.

The upper press rolls 19 to 23 are spaced in 45 arcuate arrangement with respect to the curvature of the lower roll 6 and each is in frictional contact with and driven by the lower roll. The frictional contact of each roll 19 to 23, inclusive, 50 is regulated by the tension in springs as illustrated in 21C, Fig. 4. The spring tension in turn is regulated by the plugs 27 threaded into the upper end of the guideways 19B to 23B. The plugs 27 engage the upper end of the springs 55 whose opposite end engages the bottom of the

spring pocket 28 formed in the upper end of the bearing carriers 19A to 23A, inclusive.

In practice I regulate the tension in the springs for roll 19 so that the collar or cuff will just be carried forward to roll 20 which in turn is regulated to force starch carried by the lower roll 6 thru the collar or cuff. Roll 21 is regulated to force excess starch out of the collar or cuff. Rolls 22 and 23 exert about the same pressure on the collar or cuff as does roll 21. They also serve to smooth out wrinkles so that when the collar or cuff is passed between the rolls it comes out in a smooth condition and with the high spots removed. The rolls 19 to 23 have been made of a firm rubber composition similar to wringer rolls used in the trade and have proven very satisfactory.

Mention has heretofore been made of the hinged top 17. This top 17 has been hinged to permit it to be thrown back so that the lower roll 6 may be cleaned or removed. When the top 17 is thrown back the press rolls 19 to 23 may be cleaned or removed. It is also evident that when feeding work between the rolls fingers may be caught between the rolls too. Should this happen the operator may cause the top 17 together with the press rolls 19 to 23 to be lifted away from the lower roll 6. This is brought about by the operation of the lever 29 which is pivotally secured to the top 17 and provided with a portion 30 adapted to engage the bottom face of the rib 31 of the base 1, whereby the top 17 is releasably secured to the base 1. When the top 17 has been released from the base 1 it is lifted by the compression spring 32 interposed between the two sections.

It is very evident that many deviations may be made in the design and arrangement of parts in my machine without departing from the basic

idea and therefore I do not limit my invention to the exact form shown and described but extend it to all that comes fairly within the scope of the appended claims.

I claim:

1. A collar and cuff starching machine having a driven bottom starch-carrying roll and a plurality of top press rolls cantilevered over and arranged in arcuate relation to the bottom roll and in frictional contact therewith.

2. A collar and cuff starching machine having a driven bottom starch-carrying roll, a plurality of top press rolls cantilevered over and arranged in arcuate relation to the bottom roll and in frictional contact therewith, and means for varying the frictional contact of the press rolls with the bottom roll.

3. A collar and cuff starching machine having a bottom starch-carrying roll, a multiple roll support having roll-carrying guides cantilevered over the bottom roll, a plurality of press rolls slidably mounted in the guides to frictionally contact the bottom roll, said press rolls being arranged in arcuate relation to the bottom roll, and means to vary the frictional contact between the press rolls and the bottom roll.

4. A collar and cuff starching machine having a base with a starch-carrying roll journaled therein, a top hingedly secured to the base, an upper press roll support mounted on the top and cantilevered over the starch-carrying roll, a plurality of rolls slidably mounted in the roll support to frictionally engage the upper peripheral surface of the starch-carrying roll, means to lock the top and base together, and means to separate the top and base when unlocked, said top being adapted to swing back farther to expose all the rolls for cleaning or removal.

GEORGE L. CAMPF.
